AUGUSTO BELL, OF NEAR SANTA CRUZ, CALIFORNIA

MACHINE FOR DISPOSING OF ARTICHOKE PLANTS

Application filed April 27, 1931. Serial No. 533,345.

It is the object of the present invention to provide a machine that will effectually destroy and bury artichoke plants in the field after the crop has been harvested.

5 In the drawings:

Figure 1 is a plan view of a machine embodying my invention, parts broken away.

Figure 2 is a side elevation of the same, parts broken away.

10 Figure 3 is a sectional view on line 3—3 of Figure 1.

Figure 4 is a sectional view on line 4—4 of Figure 1, parts broken away.

15 Figure 5 is a sectional view on line 5—5 of Figure 1, parts broken away.

Figure 6 is a front elevation of the chopper device.

Figure 7 is a detail view of the supporting means for the chopping knives.

20 Figure 8 is a sectional view on line 8—8 of Figure 2.

The body of the machine comprises a platform 1 mounted upon a frame 2 including a pair of forwardly projecting spaced bars 3 and 4 mounted upon a front cross bar 5 in the positions shown and to one side of its central point, and a U-shaped beam mounted on bar 5 adjacent the end remote from bars 3—4 and of greater length than bars 3—4, as shown at 6.

30 Where identical structures are shown in the accompanying drawings one structure is described in detail and the other indicated by similar numerals followed by the letter "a".

35 The body portion 1—6 is mounted upon wheels 7—7a for vertical adjustment in the following manner.

40 Considering one end of bar 5, a pair of opposed channel bars as 8—8 are vertically mounted thereon in fixed relation thereto and in spaced relation to each other to form a guide 9. Over the upper ends of these bars is mounted a bracket 10 having an upstanding bearing portion 11 formed on its inner side to receive one end of a shaft 12, the other end of the shaft being supported by a bracket 13 on platform 1 and having an operating wheel 14 mounted thereon. Slidably mounted in guide 9 is a follower or shoe 15 carrying a 45 stub shaft 16 on which wheel 7 rotates.

Mounted on shoe 15 is a threaded rod 17 extending a distance above bracket 10. A bevel gear as 18 is mounted on rod 17 to bear against bracket 10 and meshing with a bevel gear 19 on shaft 12. By means of this construction 55 operation of wheel 14 will raise or lower the structure relative to shaft 16.

In the construction just described the whole weight of the platform and parts mounted thereon is carried by the gear 18, obviously subjecting the threads to undue wear and rendering its operation difficult. To correct this I mount a collar 20 upon the upper end of rod 17 and insert coiled springs as 21 between the collar and arms 22 on the lower end of channel bars 8—8. By this means a portion of the weight is carried by rod 17 and wheel 7, yet the vertical adjustment of the structure may be readily effected by movement of the gear 18 in either direction. 60

65 The platform 1 and parts mounted thereon are adjustably supported about the axis of wheels 7—7a in the following manner. Mounted in bar 4, and in an arm 23 mounted on cross bar 5 adjacent beam 6, is a shaft 24, 70 the said shaft passing through beam 6 as indicated at 25. Mounted on shaft 24 is a frame consisting of three bars, two of the bars as 26—27 paralleling beam 6 on opposite sides thereof and converging at a point 28 forwardly of beam 6, and the other bar 29 paralleling the beam 6 but disposed near the center of the machine and converging with bars 26—27 at 28. A draft head 30 is pivotally mounted on end 28 as at 31, and wheels 32 are mounted thereon as at 33. An operating rod 34 threaded at 35 and having a handle 36 is mounted in a bearing 37 on the platform 1. A sleeve 38 is threaded on rod 34 and has a pair of links as 39 and 40 mounted on each 75 side thereof as at 41, one link being pivotally connected to beam 6 as at 42, and the other being pivotally connected to a yoke 43 on bars 26—27 as at 44.

80 By means of this construction the platform 1 and the parts mounted thereon may be tilted about the axis of the wheels 7—7a as desired by rotating the rod 34 in either direction, the links 39—40 operating to swing the beam 6 in a vertical plane about shaft 24. 85

- A trench forming plow is mounted on bar 29 in the following manner. The plow share 45 is provided with an arm 46 passing upwardly through a guide 47 on bar 29 where it is pivotally connected as at 48 to an operating lever 49 fulcrumed on bar 29 as at 50 and provided with a foot pedal at 51 overlying platform 1. The lever may be locked in any suitable position by engagement with an upward standing ratchet 52 on platform 1. A second arm 53 is mounted on the share 45 and is directed upwardly and forwardly a distance as shown and provided with a terminal finger 54 passing upwardly through a guide 55 in 15 which it is pivoted by means of a pin 56. By operating lever 49 the plow may be vertically adjusted and its effective working angle changed as desired relative to the frame 26—27—29.
- 20 The bulky top of the plant is chopped up in the following manner. A shaft 57 is vertically mounted in bearings 58 mounted on bar 5 and extending forwardly thereof in the position shown, the shaft being actuated by gear and shaft connections 59 to a motor 60 on platform 1. On shaft 57 are vertically spaced and horizontally disposed knives 61. A shield 62 is mounted on bars 3 and 4 rearwardly of shaft 57, and a number of fingers 63 are mounted on one edge of the shield to extend inwardly between the several knives.
- 25 As the machine moves along the row of plants the rapidly rotating knives cut each plant into small parts which the shield throws to the ground in front of the scraper hereinafter described.
- 30 The scraper 64 is mounted on the under side of frame 2 and is provided with a cutting edge 65 disposed to move substantially at the surface of the ground to cut the stalks of the plants at the ground level. The scraper is scoop shaped and is angularly disposed, extending from a point rearwardly of the outer side of shield 62 to a point beneath 35 the rear edge of platform 1 and back of the plow 45, whereby material cut as described will be gathered up and carried a distance laterally and discharged into the trench formed by the said plow.
- 35 It may now be seen that I have provided a machine that may be drawn over a field down a row of artichoke plants, with the plow forming a trench along side of the row, the chopper cutting each plant into small pieces, and the scraper depositing the cut material in the trench. The scraper also gathers up sufficient soil to cover the material after it is deposited in the trench.
- 40 The vertical adjustments actuated by hand wheels 14—14a permit the scraper to be raised or lowered or tilted endwise to any desired degree, and the adjustment effected by rod 34 permits the scraper to be tilted as desired about the axis of the wheels,

while the plow may be adjusted as desired independently of the scraper.

It is to be understood, of course, that while I have herein shown and described but one specific embodiment of the invention, changes in form, construction, and method of assembly and operation may be made within the scope of the appended claims.

I claim:

1. A machine of the character described comprising, a vehicle trench forming means mounted thereon, plant chopping means mounted thereon and laterally spaced from the trench forming means and adapted to engage and chop the standing stalks, and a scoop having a cutting edge formed thereon mounted on the vehicle rearwardly of the chopping means and disposed at an angle to the line of draft of the vehicle whereby to cut down the unchopped portions of the stalks and to gather the chopped and cut material and deposit it in the trench formed by the trench forming means.

2. A machine of the character described comprising, a frame and supporting wheels therefor, a beam mounted thereon and extending forwardly thereof, a second frame pivotally mounted thereon and extending forwardly thereof in parallel relation to the said beam, draft means pivotally connected to the second frame and supporting wheels therefor, a plow operatively mounted on the second frame, plant chopping means mounted on the first frame and spaced laterally from said plow, a scoop scraper mounted on the first frame rearwardly of the chopping means and adapted to discharge rearwardly of the plow, and means for tilting the first frame relative to the second frame.

3. A machine of the character described comprising, a frame and supporting wheels therefor, a beam mounted thereon and extending forwardly thereof, a second frame pivotally mounted thereon and extending forwardly thereof on both sides of said beam, wheel supported draft means pivotally connected to said second frame, a yoke mounted on the second frame, a pair of links pivotally connected to each other and to said yoke and beam, a sleeve connected to said links at the point of their pivotal connection, a rod threaded into said sleeve, a bearing for the rod and means for holding the rod against longitudinal movement whereby rotation of the rod will actuate the links to tilt the beam and first frame relative to the second frame, a plow mounted on the second frame, material chopping means mounted on the first frame, and a scoop scraper mounted on the first frame rearwardly of the chopping means and adapted to discharge rearwardly of the said plow.

4. A machine of the character described comprising, a pair of supporting wheels, a frame tiltably mounted thereon, means for

vertically adjusting either end of the frame thereon, a beam mounted on the frame and extending forwardly thereof, a second frame pivotally mounted with respect to the first frame, means for tilting the first frame with respect to the second frame inserted between the second frame and forward end of the beam, supporting wheels mounted on the forward end of the second frame, a plow mounted on the second frame, plant chopping means mounted on the first frame, and a scoop scraper mounted on the first frame rearwardly of the chopping means and adapted to discharge rearwardly of the said plow.

5. In a device of the character described, a platform, a vertically disposed guide mounted on each end thereof, a follower disposed in each guide and having a wheel mounted thereon, a threaded rod mounted on each follower and extending upwardly through the top of the guide, a gear on each rod engaging the overlying top of the guide, means for rotating the gear in either direction whereby to raise or lower the platform relative to the wheels, and resilient means connecting the top of the rod and the guide whereby to carry a portion of the weight of the platform and parts mounted thereon on the wheels through the medium of the said

30 followers and rods.

6. A machine of the character described comprising a pair of supporting wheels, a frame tiltably mounted thereon, means for vertically adjusting either end of the frame thereon, a second frame pivotally mounted with respect to the first frame, means for tilting the first frame with respect to the second frame, supporting wheels mounted on the second frame, a plow mounted on the second frame, plant chopping means mounted on the first frame, and a scoop scraper mounted on the first frame rearwardly of the chopping means and adapted to discharge rearwardly of the said plow.

45 AUGUSTO BELLi.
